UNITED STATES PATENT OFFICE.

ADOLPH WAHLE, OF DAVENPORT, IOWA.

CASING FOR MECHANICAL MOVEMENTS.

SPECIFICATION forming part of Letters Patent No. 732,977, dated July 7, 1903.

Application filed February 9, 1903. Serial No. 142,531. (No model.)

To all whom it may concern:

Be it known that I, ADOLPH WAHLE, a citizen of the United States, and a resident of Davenport, in the county of Scott and State 5 of Iowa, have invented certain new and useful Improvements in Casings for Mechanical Movements, of which the following is a full, clear, and exact description.

Heretofore the mechanical movements for washing-machines, churning, and similar machines, and particularly mechanism employed for converting the continuous rotary movement of a suitable fly-wheel turned by the operator into a rotary reciprocal movement 15 of the vertical stirrer-shaft, have been exposed and frequently children meddling with the same have been injured and clothing and articles of the wash accidentally caught thereby and chewed and torn.

20 The object of my invention is to house such mechanism in a cheap and economical manner without much addition to the supporting-frame said mechanism would have to employ in any event and so as to prevent rust and avoid the possibility of the above-indicated as well as other accidents. This I accomplish by the means hereinafter fully described, and particularly pointed out in the 25 claims.

30 In the drawings, Figure 1 is a side elevation of my invention. Fig. 2 is a plan view of the same. Fig. 3 is a vertical longitudinal central section. Fig. 4 is a section taken on line 4-4, Fig. 3, looking in the direction of the arrows. Fig. 5 is a detail view of the lower section.

In the drawings, A represents a longitudinal trough-shaped frame the outer end of 40 which is supported by spreading legs *a a* and terminates in bearing *b*. The opposite or inner end of this frame A terminates in a semi-spherical cup-shaped lower section B of the case in which it is designed to house mechanism for converting the continuous rotary motion of a shaft C, journaled in bearing *b* and bearing *c*, located near the opposite end of frame A, into a rotary reciprocal motion of the perpendicular shaft D, journaled in bearing *d* in the center of the bottom of section B, and in bearing *e*, diametrically opposite thereto in the top of the upper section E of said case.

The bottom section B is provided with a concentric boss *f*, down through the center of which the bearings of shaft D extend, and this boss extends downward a suitable distance below its plane of rest, so as to anchor and prevent its displacement in a horizontal position in any direction. On each side of this boss there extends downward from the 55 sides of section B a short tubular column *g g*, down through which a suitable screw is inserted and screwed into the material of its support. If desired, the upper ends of the bores of these columns may be countersunk 60 to accommodate the heads of the screws.

The upper semispherical section E of the case corresponds in dimensions to the lower section B, and the annular edges of these sections B and E are brought together to form 70 a butt-joint and are secured in this position by means of suitable bolts *i i*, extending through radial lugs *j* and *k*, projecting from the edges of said sections, respectively. At the point where the shaft C enters the case the upper 75 section is provided with an inverted semicircular stub F, projecting therefrom parallel and concentric to shaft C. The projection of this stub is such that it overlaps the adjacent end of bearing *c* of frame A and its parallel edges rest upon the side edges of the channel or gutter of said frame, which between bearing *c* and section B is slightly wider.

At a point preferably between the bearings *e* of the vertical shaft D and bearings *c* of shaft C, I provide the upper section with a grated opening G, the spaces between the bars of which are large enough to insert the nozzle of an oil-can and easily oil the mechanism housed within the case, and in the bottom of section B an opening *h* is provided for draining off the superfluous oil. In order, however, to prevent the oil from getting into the bearing *d* of said lower section, I have provided the interior surface of said section with a suitable circular or other endless shaped bead H, which is eccentric to bearings *d* and is so located as to cause the oil dripping from the actuating mechanism falling outside of 95 it to drain into and out of opening *h*.

While I have illustrated and described the upper and lower sections of the case as semispherical, it is obvious they can be made other

shapes to accommodate the peculiarities in the shape and disposition of the actuating mechanism, for while I have illustrated actuating mechanism which is described and claimed in Letters Patent of the United States granted to me July 22, 1902, I do not wish to be understood as limiting myself to an inclosing case or frame only for such mechanism.

What I claim as new, and desire to secure by Letters Patent, is—

1. A casing for mechanical movements comprising a supporting-frame having bearings therein for the drive-shaft, a lower hollow section at one end of said supporting-frame having bearings in its bottom arranged at right angles to the bearings in said supporting-frame, and an upper inverted hollow section, secured to said lower section.

2. A casing for mechanical movements comprising a supporting-frame having bearings therein for the drive-shaft, a lower hollow section cast in one piece with one end of said supporting-frame having bearings in its bottom arranged at right angles to the bearings in said supporting-frame, and an upper inverted hollow section, secured to said lower section.

3. A casing for mechanical movements comprising a supporting-frame having bearings therein for the drive-shaft, a lower hollow section cast in one piece with one end of said supporting-frame having bearings in its bottom arranged at right angles to the bearings in said supporting-frame, and an upper inverted hollow section, secured to said lower section having bearings in its top diametrically opposite the bearings in the bottom of the lower section.

4. A casing for mechanical movements comprising a supporting-frame having bearings therein for the drive-shaft, a lower hollow section at one end of said supporting-frame having bearings in its bottom arranged at right angles to the bearings in said supporting-frame having an oil-drain opening in its bottom near said bearings, and an upper inverted hollow section, secured to said lower section having an oil-opening in its top.

5. A casing for mechanical movements comprising a supporting-frame having bearings therein for the drive-shaft, a lower hollow section at one end of said supporting-frame having bearings in its bottom arranged at right angles to the bearings in said supporting-frame having an oil-drain opening in its bottom near said bearings, and an upper inverted hollow section, secured to said lower section having a grated oil-opening in its top.

6. A casing for mechanical movements comprising a supporting-frame having bearings therein for the drive-shaft, a lower hollow section at one end of said supporting-frame having bearings in its bottom arranged at right angles to the bearings in said supporting-frame, having an oil-drain in its bottom near said bearing and a bead for shedding the superfluous oil into said drain-opening,

and an upper inverted hollow section, secured to said lower section having an oil-opening in its top.

7. A casing for mechanical movements comprising a supporting-frame having bearings therein for the drive-shaft, a lower hollow section at one end of said supporting-frame having bearings in its bottom arranged at right angles to the bearings in said supporting-frame, having an oil-drain in its bottom near said bearings, and a circular bead surrounding and eccentric to said bearings for shedding the superfluous oil into said drain-opening, and an upper inverted hollow section, secured to said lower section having an oil-opening in its top.

8. A casing for mechanical movements comprising a supporting-frame having bearings therein for the drive-shaft, a lower hollow section cast in one piece with one end of said supporting-frame having bearings in its bottom arranged at right angles to the bearings in said supporting-frame, having an oil-drain in its bottom near said bearings and a bead for shedding the superfluous oil into said drain-opening, and an upper inverted hollow section, secured to said lower section having an oil-opening in its top.

9. A casing for mechanical movements comprising a supporting-frame having bearings therein for the drive-shaft, a lower hollow section cast in one piece with one end of said supporting-frame having bearings in its bottom arranged at right angles to the bearings in said supporting-frame, having an oil-drain in its bottom near said bearings, and a circular bead surrounding and eccentric to said bearings for shedding the superfluous oil into said drain-opening, and an upper inverted hollow section, secured to said lower section having an oil-opening in its top.

10. A casing for mechanical movements comprising a gutter-shaped supporting-frame having bearings in its outer end and bearings in its inner end, a lower hollow section cast in one piece with the inner end of said supporting-frame, which has a downwardly-projecting bearing-boss in its bottom the bore of which is arranged at right angles to the bearing in the supporting-frame, and has an oil-drain in the bottom thereof near said bearing, and a bead for shedding the superfluous oil into said oil-drain, and an upper inverted hollow section having bearings in its top diametrically opposite the bearings in the lower section, and having a semicircular stub covering the gutter of said supporting-frame between the adjacent bearing therein and said case.

11. A casing for mechanical movements comprising a gutter-shaped supporting-frame having bearings in its outer end and bearings in its inner end, a lower hollow section cast in one piece with the inner end of said supporting-frame, which has a downwardly-projecting bearing-boss in its bottom the bore of which is arranged at right angles to the bear-

ing in the supporting-frame, and has an oil-drain in the bottom thereof near said bearings, and a bead for shedding the superfluous oil into said oil-drain, and an upper inverted 5 hollow section having bearings in its top diametrically opposite the bearings in the lower section, and having a semicircular stub covering the gutter of said supporting-frame between the adjacent bearing therein and said 10 case, said upper and lower sections having

their annular edges meeting and provided with radially-projecting lugs, and bolts extending through said lugs for securing said sections together.

In testimony whereof I have hereunto set 15 my hand this 2d day of February, 1903.

ADOLPH WAHLE.
